SUCTION CLEANER

Filed March 2, 1932

UNITED STATES PATENT OFFICE

HARRY B. WHITE, OF CANTON, OHIO, ASSIGNOR TO THE HOOVER COMPANY, OF NORTH CANTON, OHIO, A CORPORATION OF OHIO

SUCTION CLEANER

Application filed March 2, 1932. Serial No. 596,189.

The present invention relates to suction cleaners and more particularly to new and novel means in a suction cleaner to prevent the operation of the cleaner with the driving belt incorrectly connected between the rotary agitator and the motor drive shaft. More specifically the invention comprises a signaling device which functions only when the power-transmitting belt between the motor drive shaft and the agitating means in the suction cleaner nozzle is incorrectly connected to the drive shaft. In view of the desirability of having the suction cleaner agitator rotate in a certain direction, and further in view of the desirability of obtaining maximum belt life, together with uninterrupted service, the usefulness of the present invention which insures those things is apparent.

It is an object of the present invention to provide new and novel means to apprise the suction cleaner operator of the fact that the power-transmitting belt between the rotary agitator in the suction cleaner nozzle and the drive-shaft is incorrectly attached. A further object is to provide warning means, making use of audible sounds, to inform the cleaner operator of the incorrect connection existing in his cleaner. Still another object is the provision, in a suction cleaner of noise-creating-warning means which are automatically operated when the cleaner is operated with the belt reversed at its connection to the motor shaft. These and other more specific objects will appear upon reading the following specification and claims and upon considering in connection therewith the attached drawing to which they relate.

Referring now to the drawing in which the same reference character refers to like parts in the various views:

Figure 1 is a side view of a modern suction cleaner with the present invention embodied therein, the cleaner being shown partly in section;

Figure 2 is a partial bottom view of the cleaner shown in Figure 1 with the bottom plate broken away to show the interior of the machine;

Figure 3 is a partial view similar to Fig-

ure 1, showing the belt incorrectly connected to the motor shaft;

Figure 4 is a top view looking down upon a detail of the present invention detached from the cleaner body;

Figure 5 is a section upon the line 5-5 of Figure 4;

Figure 6 is a partial section upon the line 6-6 of Figure 2 showing the clearance between the power-transmitting belt and the noise-creating device when the belt is correctly connected to the drive shaft.

A modern suction cleaner is shown in the drawing and comprises a main casing indicated generally by the reference character 1 which includes the suction nozzle 2, the fan chamber 3, which is interiorly connected through its eye 4, to the air passageway 5 extending from the nozzle 2 to the fan chamber, and an exhaust outlet 6 to which is detachably connected by suitable means 7 a dust bag 8. The air passageway between the nozzle 2 and the fan chamber 3 is closed by a detachable bottom plate 9, the forward end of which forms a rear nozzle lip 10, the front nozzle lip 11 being carried by the nozzle proper 2.

Positioned upon the main casing 1 immediately over the fan chamber 3 is the motor casing 12 which houses a suitable driving motor, the shaft 13 of which extends downwardly through the fan chamber 3, through the eye 4 of the fan chamber, and into the air passageway 5 where it is convexly shaped as a pulley. Carried by the motor shaft 13 within the fan chamber 3 is a suction-creating fan 14 whose function is to create a reduced pressure within the fan chamber resulting in the drawing of cleaning air into the nozzle 2 between the lips 10 and 11, through the air passageway 5 and fan chamber inlet 4, and into the fan chamber from whence it is exhausted through the exhaust outlet 6 into the dust bag 8. The entire cleaner is movably supported by front wheels 15, 15 and by rear wheels of which only one is shown, being indicated at 16 but which are provided with height-controlling means 17 by which they can be raised or lowered, relative to the cleaner body, for the

purpose of raising or lowering the nozzle 2 relative to the surface covering undergoing cleaning. As in the usual cleaner construction a handle 18 is provided which is pivotally connected to the main body 1 at the side of fan chamber 3 and which is provided with position-retaining means indicated generally by the reference character 19.

Within the nozzle 2 of the cleaner and rotatably supported by a transverse shaft 20 is a rotatable agitator 21 which comprises a cylindrical body upon the surface of which are positioned helically extending raised beater elements 22, 22. A longitudinally extending brush 23 is also carried by the agitator body and there is positioned substantially midway of the length of agitator a surface of reduced diameter which forms a pulley 24. Connecting the pulley 24 to the pulley surface of shaft 13 is a power-transmitting belt 25 whose function it is to rotate the agitator 21 by means of the power it transmits from the motor shaft 13.

In the operation of the suction cleaner it is extremely desirable that the rotary agitator 21 revolve in a counterclockwise direction as viewed in Figure 1 and as indicated by the arrow in that figure. It is necessary in order to have a stable condition without slippage that the tension side of the belt should extend substantially perpendicularly to the drive shaft, and with the shaft rotating in the direction of the arrow in Figure 1 it is clear that the lower side of the belt is the tension side and that the desired relationship exists. With the belt so connected the pull upon the lower side of the belt 25 is in a straight line and there is no tendency for the belt to climb in either direction upon pulley 13. If, however, in the replacing of a belt the operator connects the belt in the opposite and wrong relationship with shaft 13, or that shown in Figure 3, in which the top side of the belt passes around the near side of the pulley, it is then clear that the belt will tend to climb upwardly upon the pulley in an attempt to decrease the distance between the point at which it leaves the pulley 24 and the point at which it contacts the pulley 13. A reversal of direction of rotation of agitator 21 also results and is undesirable as the brush and beater elements of the agitator throw the foreign matter which they contact outwardly from the cleaner nozzle 2 and under the front lip 11 instead of rearwardly and into the air passageway 5 as in the normal operation of the cleaner. The condition is also undesirable for as the belt climbs upwardly upon the shaft 13 its movement thereafter results in its being worn by contact with the underside of fan chamber 3. The sliding of belt 25 in contact with fan chamber 3 also tends to place an undue load upon the driving motor which may be injurious though only temporary. According to the present

invention the pulley diameter of shaft 13 decreases as the shaft approaches fan 14 so that with the belt rubbing against the fan chamber and increasing the load on the belt the belt speed is materially reduced thereby maintaining substantially the same load on the shaft 13 and the driving motor.

In the suction cleaner constructed in accordance with the present invention, means are also provided which inform the operator of the fact that the belt is incorrectly connected when that is the case. A forwardly extending arm 26 is pivotally mounted within the suction nozzle 2 upon a pin 27 carried by a U-shaped bracket 28 which is itself mounted upon the forward facing side wall of the fan chamber 3. The arm 26 also extends downwardly from the pivot pin 27 in a substantially vertical direction, and is contacted by a coil spring 29 carried by bracket 28 which exerts a force on arm 26 resulting in the forward end of that member being forced up against the wall of nozzle 2 immediately above the rotary agitator 21. From a point immediately below the bracket 28 the arm 26 extends rearwardly as a lever to a position immediately over the normal position of the belt 25 as is clearly seen in Figure 1. With the belt in the normal position upon the driving pulley 13 it passes under this rearward or lever portion of arm 26 without any contact therebetween. If, however, the belt is incorrectly connected, as shown in Figure 3 of the drawing, the belt climbs up the pulley to the position there shown and functions to lift the rear portion of arm 26 upwardly, thereby pivoting downwardly the forward portion of that arm against the pressure exerted by coil spring 29. The forward portion of arm 26 is thereupon contacted by the rotating beating elements 22, 22 at high frequency resulting in a considerable sound disturbance or racket which is completely effective in calling the attention of the operator to the situation that exists.

I claim:

1. In a suction cleaner, a driving shaft, a movable agitator including surface-contacting elements, removable power-transmitting means between the shaft and the agitator adapted to assume a plurality of positions relative to said shaft, signalling means adapted to be operated by said power-transmitting means in certain positions on said shaft, and means to maintain said signalling means inoperative with said power-transmitting means in certain positions on said shaft.

2. In a suction cleaner, a driving shaft, a movable agitator including surface-contacting elements, removable power-transmitting means between said shaft and said agitator adapted to assume a plurality of positions relative to said shaft, audible signalling

means adapted to be operated by said power-transmitting means in certain positions on said shaft, and means to maintain said signalling means inoperative with said power-transmitting means in certain positions on said shaft.

3. In a suction cleaner, a driving shaft, a movable agitator including surface-contacting elements and a pulley surface, a removable power-transmitting belt connected between said shaft and the pulley surface of said agitator and adapted to be connected to said shaft in a plurality of ways, means adapted to be contacted by said belt when connected to said shaft in a certain way, and signalling means connected to said first-mentioned means and operated upon said belt contacting said first-mentioned means.

4. In a suction cleaner, a driving shaft, a movable agitator including surface-contacting elements and a pulley surface, removable power-transmitting means between said shaft and the pulley surface of said agitator and adapted to be connected to said shaft in one of a plurality of ways, means adapted to be contacted and actuated by said power-transmitting means in a certain position, and signal means operable by said first-mentioned means.

5. In a suction cleaner, a nozzle, a rotary agitator in said nozzle, a driving shaft, a removable belt between said agitator and said shaft adapted to make contact with the latter at a plurality of longitudinally spaced points, means adapted to be contacted by said belt when it contacts said shaft at a certain point, and means in said nozzle adapted to be moved into contact with said agitator to create a noise upon said first-mentioned means being contacted by said belt.

6. In a suction cleaner a body including a nozzle, a rotary agitator in said nozzle, a drive shaft spaced from said agitator, a belt connected between said agitator and said shaft and adapted to encircle said shaft in one of two directions, a lever pivotally carried by said body and adapted to be contacted by said belt when it encircles said shaft in one direction, and signal means operatively connected to said lever.

7. In a suction cleaner, a body, a rotary agitator carried by said body, a drive shaft carried by said body and spaced from said agitator, a belt between said agitator and said shaft adapted to make contact at longitudinally spaced points on said shaft, a lever pivotally carried by said body adapted to be contacted and pivoted by said belt in one of its positions on said shaft, and an arm carried by said body and connected to said lever and adapted to be moved into contact with said agitator upon the pivoting of said lever.

8. In a suction cleaner, a body, a rotary agitator carried by said body including

radially projecting portions, an element carried by said body adapted to contact said portions in certain of its positions to create a noise, a driving shaft carried by said body at right angles to the axis of said agitator, a power-transmitting belt between said shaft and said agitator adapted to be connected to said shaft so that either side of said belt from said agitator passes around either side of said shaft, a lever carried by said body positioned adjacent said belt and adapted to be contacted and moved thereby with said belt connected to said shaft in one relationship, said lever being connected to said element and adapted to move said element into contact with said portions.

9. In a suction cleaner, a body, a rotary agitator carried by said body, a drive shaft formed with a pulley surface carried by said body and spaced from said agitator, a belt connected between said agitator and said shaft, the tension side of said belt extending substantially perpendicularly to said shaft at its normal point of belt contact, said belt being adapted to be reversely connected to said shaft, means obstructing the path of the belt in the reversed relationship and adapted to increase the load thereon by rubbing contact therewith, said pulley surface being of reduced diameter at the normal point of belt contact with said belt reversed for the purpose of reducing the load on said belt and shaft to offset the additional load.

Signed at North Canton, in the county of Stark and State of Ohio, this 25th day of February A. D., 1932.
